[57] CLAIM

The ornamental design for a mitt used for bathing, as shown and described.

DESCRIPTION

FIG. 1 is a top plan view of a mitt used for bathing embodying our new design;

FIG. 2 is a sectional view taken along line 2—2 of FIG. 1;

FIG. 3 is a sectional view taken along line 3—3 of FIG. 1;

FIG. 4 is a sectional view taken along line 4—4 of FIG. 1;

FIG. 5 is a bottom plan view thereof;

FIG. 6 is a side elevational view as seen from the right of FIG. 5;

FIG. 7 is a left side elevational view thereof;

FIG. 8 is a front end elevational view thereof;

FIG. 9 is a rear end elevational view thereof; and,

FIG. 10 is a rear perspective view thereof.

The crosshatched pattern, which is partially shown for ease of illustration, represents a conventional material and is understood to repeat throughout the areas indicated. The broken lines shown at the bottom of the mitt in FIGS. 1, 6 and 7 represent conventional stitching.
